DESIGN FOR A HUMIDITY AND TEMPERATURE THERMOMETER CASE OR SIMILAR ARTICLE

Garfield L. Beckstrom, Chicago, Ill., assignor to Autopoint Company, Chicago, Ill., a corporation of Illinois

Application October 25, 1944, Serial No. 115,961

Term of patent 14 years

(Cl. D52—7)

To all whom it may concern:

Be it known that I, Garfield L. Beckstrom, a citizen of the United States, residing at Chicago, in the county of Cook and State of Illinois, have invented a new, original, and ornamental Design for a Humidity and Temperature Thermometer Case or Similar Article, of which the following is a specification, reference being had to the accompanying drawing, forming a part thereof.

In the drawing:

Fig. 1 is a front elevation of a humidity and

temperature thermometer case or similar article embodying my new design.

Fig. 2 is a top plan view thereof.

Fig. 3 is a side elevation looking toward the right hand side of Fig. 2.

I claim:

The ornamental design for a humidity and temperature thermometer case or similar article, substantially as shown.

GARFIELD L. BECKSTROM.
